United States Patent Office

Des. 215,717
Patented Oct. 28, 1969

215,717

COMBINED BATHTUB AND SHOWER ENCLOSURE

Kay L. Ruggles and Norman Van Skyhawk, Salt Lake
City, Utah, assignors to American Standard Inc., New York, N.Y., a corporation of Delaware

Filed June 10, 1968, Ser. No. 12,275

Term of patent 14 years

Int. Cl. D23—02

U.S. Cl. D23—49

Fig. 1.

Fig. 2.

The broken line showing of plumbing in FIG. 2 is for purposes of illustration only.

We claim:

The ornamental design for a combined bathtub and shower enclosure, as shown and described.
